UNITED STATES PATENT OFFICE.

CHARLES E. HAYES, OF BROCKTON, MASSACHUSETTS.

THREAD-FEEDING ATTACHMENT FOR SEWING-MACHINES.

1,151,585.

Specification of Letters Patent. Patented Aug. 31, 1915.

Application filed August 21, 1914. Serial No. 857,884.

To all whom it may concern:

Be it known that I, CHARLES E. HAYES, a citizen of the United States, residing at Brockton, in the county of Plymouth and State of Massachusetts, have invented certain new and useful Improvements in Thread-Feeding Attachments for Sewing-Machines, of which the following is a specification.

This invention relates to improvements in sewing machine attachments and more particularly to thread feeding apparatus.

The object in view is the increase in the effective feeding of the thread by subjecting the thread substantially at the point of supply to a resistance sufficient for tensioning the thread in the course of being supplied to the needle.

With this and further objects in view, as will in part hereinafter become apparent and in part be stated, the invention comprises a movable spool carrier, and a bracket upstanding therefrom and having frictional guiding means for thread delivered from a spool sustained by the spool carrier.

The invention comprises certain other novel constructions, combinations and arrangements of parts as will be hereinafter specified and claimed.

In the accompanying drawing: Figure 1 is a view in side elevation of a fragment of a sewing machine having applied thereto the apparatus embodying the features of the present invention. Fig. 2 is a similar view of the same detached, parts being broken away for the saving of space and parts being seen in vertical section. Fig. 3 is a vertical section taken on the plane indicated by the line 3—3 of Fig. 2, parts being seen in elevation.

Referring to the drawings by numerals, 1 indicates the usual arm of a sewing machine, from which upstands the spool sustaining spindle 2. The arm 1 and usual mechanism of the sewing machine is sustained on an ordinary table 3 on which is mounted a stand 4 which is preferably retained in place by securing means extending through an aperture 4' in the stand engaging the table. The stand 4 is formed with a vertical passageway which registers with an aperture in the table and is adapted to receive a rod 5. The rod 5 is surrounded by a collar 6 which is locked in position on the rod 5 by a set screw 7 so that the rod will be sustained upon the stand 4 and still free to revolve relative thereto. A set screw 8 is threaded

through a portion of the stand 4 into engagement with the rod 5 for gripping the rod and maintaining the same in a given adjusted position. The rod 5 is bent to form an offset horizontal portion 9 producing a bracket having an upstanding portion fixed to a disk or plate 10. The means of connection between the bracket and plate is susceptible of a wide range of variation but preferably consists of threads, the rod being externally threaded and engaging internal threads of an aperture in the plate. Preferably the rod engages the plate centrally thereof, and the plate at the central point is provided with an upstanding shank 11 which is formed with a bore from beneath for receiving the threaded end of the bracket rod. The shank 11 serves the useful purpose of forming a bearing for a spool or other thread container 12 rotatably resting upon plate 10. A short shaft 13 extends into the upper end of the spool 12 and carries a revolvably mounted disk 14 disposed above the upper end of the spool and provided with a thread guiding aperture 15 at one point, the disk being preferably formed with a thickened rounded portion 16 having a curved wall approaching the aperture 15 for preventing the presentation of a sharp corner to a thread fed from the spool through the aperture 15.

A rod or arm 17 has its lower end fixed to plate 10 and extends upwardly to a point considerably above the plane of the upper end of the spool 12 and is bent thence to form an overhanging portion 18 having its free end approximately overhanging the central portion of spool 12. Rod 17 and the portion 18 are formed with guiding eyes 19 or apertures 19, 19, and the thread from spool 12 is extended through aperture 15 and thence through the aperture 19 at the free end of portion 18 and then successively through the several apertures 19 to the lower end of the rod, the thread being preferably wrapped about the rod in its progress along the rod for increasing the frictional resistance to longitudinal travel of the thread.

In operation, the structure being threaded in the manner described and shown in Fig. 3 the thread is passed about the spindle 2 and thence to the needle feeding mechanism so that the approach of the thread to said mechanism is substantially the same as when thread is threaded from a spool carried by spindle 2, while the advantage of the

frictional resistance to the feeding of the thread is obtained. As the thread is being fed the disk 14 will revolve for keeping the aperture 15 nearest the point of discharge 5 of the thread from the spool 12. When it is desired to oil the mechanism of the sewing machine, the arm 1 is swung backwardly in the usual manner but before doing so the set screw 8 is unloosened and the spool 12 10 with all connected parts are swung around to the dotted position indicated in Fig. 1 and the parts are thus entirely out of the path of movement of the arm with its connected parts. When the arm is restored the bracket rod is returned for restoring the spool supporting plate 12 and the set screw 8 is tightened on the rod. The disk 14 is 15 preferably mounted upon the shaft 13 between a pair of felt washers 20, a screw 21 20 or similar fastening member passing through the washer and disk into said shaft. The object in view is to provide friction which will prevent the disk from spinning around during rotation on its shaft 13 as 25 will be obvious.

Having thus described the invention, what claim as new is:

1. In a sewing machine attachment, the combination of a stand adapted to be applied to the table of a sewing machine adjacent the rear portion of the arm thereof, a bracket rod revolvably engaging the stand and having an offset portion and an up-standing portion at one terminus of the off-set portion adapted to be disposed adjacent 30

the spool receiving spindle of the sewing machine arm, detachable spool sustaining means having adjustable connection with the upstanding portion of the rod aforesaid, and a locking element carried by said upstanding portion adapted for co-operation with the spool sustaining means to hold the same at adjusted positions. 40

2. In a sewing machine attachment, the combination of a stand adapted to be applied to the table of a sewing machine adjacent the rear portion of the arm thereof, a bracket rod revolvably engaging the stand and having an offset portion and an up-standing portion at one terminus of the offset portion adapted to be disposed adjacent the spool receiving spindle of the sewing machine arm, a spool sustaining member having adjustable connection with the up-standing portion of said rod, said member comprising a plate having threaded connection with the rod and formed with a spindle to receive a spool, said spindle being recessed to receive the extremity of the up-standing portion aforesaid, and a clamping nut on the upstanding portion beneath the spool sustaining plate for holding said plate at adjusted positions. 45

In testimony whereof I affix my signature in presence of two witnesses.

CHARLES E. HAYES.
